(57) **CLAIM**

The ornamental design for a hinged apparatus for a cup, as shown and described.

DESCRIPTION

FIG. 1 is a perspective view of my new design for a hinged apparatus for a cup;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a top view thereof; and,

FIG. 7 is a bottom view thereof.

The broken lines shown in the drawing views are included for the purpose of showing environmental structure that forms no part of the claimed design.
